UNITED STATES PATENT OFFICE.

GEORGE J. HENRY, OF SAN FRANCISCO, CALIFORNIA.

RADIANT REFLECTOR.

1,393,368.

Specification of Letters Patent. Patented Oct. 11, 1921.

Application filed March 10, 1920. Serial No. 384,769.

To all whom it may concern:

Be it known that I, GEORGE J. HENRY, a citizen of the United States, and a resident of the city and county of San Francisco, State of California, have invented new and useful Improvements in Radiant Reflectors, of which the following is a specification.

My invention has for its object the forming of a reflector for radiant energy such that a beam reflected on the surface of the reflector and originating at an energy source substantially, at the focus thereof, will be reflected outwardly as a diverging beam from the reflector; as distinguished from earlier forms wherein a beam reflected therefrom converges, crossing the axis of the curve of the reflector, or if of a parabolic form, emanates as a beam whose rays are parallel with the axis of the paraboloid.

My invention is particularly adapted to heaters of the radiant type in which the beam of radiant energy is directed from the reflecting surface, and when the reflected rays of such a beam strike an object on their path, they are transformed into heat energy thereby heating the object.

A further object of my invention is providing within the space between the reflector and the heat unit a supplementary reflector of relatively smaller dimensions, which receives the most direct rays emanating from the heat unit and reflects them to the surface of the larger reflector when they are again reflected outward, or divergent and clear of the heat unit. By this supplementary reflecting curved surface I prevent the concentration of reflected rays back upon the surface of the heat unit, and which have heretofore been accompanied by the early destruction of that portion of the heat unit thus subjected to this excessive heating.

Or, the reflector may be formed at its central portion with a cusp, or supplementary reflecting curved surface whereby the said direct energy rays instead of being reflected back on the adjacent portion of the heat unit are directed away from such path.

With my invention the reflector, and especially the central portion thereof, is kept cooler than in types heretofore employing the continuous curved or flat surface of the reflector with its concave surface toward the heat unit.

By referring to the accompanying drawings my invention will be made clear.

Figure 1 illustrates my hyperbolic form

of reflector having a supplementary reflecting surface of relatively smaller dimensions at its central portion for diverging the direct rays of the heat unit.

60

Fig. 2 shows my supplementary form of reflector mounted at the center of a parabolic form of reflector and spaced therefrom.

Fig. 3 illustrates the path of the radiant energy which has heretofore resulted in the early destruction of heat units due to the reflected rays from the center of the reflector.

Fig. 4 shows the manner in which said rays when reflected are diverted from the surface of the heat unit.

Fig. 5 shows the manner of constructing the hyperbolic curve of my reflector.

Throughout the figures the same numerals refer to identical parts.

A heat unit adapted to emanate radiant energy, as an electrical resistance, is indicated by the numeral 1, which is preferably mounted at the focus of a curved reflector adapted to reflect radiant energy, such a reflector of hyperbolic form, is indicated by the numeral 2, and a reflector of parabolic form is indicated by numeral 3.

Radiant energy emanates from the unit 1 in straight lines, as indicated by the rays 4, 5, 6, 7, which are received upon the surface of the reflectors 2 and 3. The ray 5 is reflected from the surface of 2 in the direction of the arrow 8, the angle of incidence 90 being equal to the angle of reflection. Due to the properties of the hyperbola the reflected ray 8 will be divergent, the heat unit 1 being mounted at one of the focii of the said hyperbola. The degree of divergence 95 of the ray 8 is dependent upon the degree of curvature of 2, which again is dependent upon the relative position of the focii 1 and 9 (Fig. 5). If the surface 2 be revolved about the axis 10, a hyperboloid (or hyperbola of revolution) will be formed, and the rays as 8 and 11 from the entire surface will form collectively a radiant beam diverging into space as it issues from the reflector.

These rays will not cross the axis 10 and 105 therefore a relatively even distribution of the energy in the space in front of the reflector 2 will be secured with the least danger of fire due to the concentration of rays where they would cross the axis in other 110 forms.

In Fig. 2 the well known form of parabola

is shown, in which rays, as 6, striking the surface of 3 from the energy source 1, will issue from the surface of the parabola as indicated by the arrow 12, parallel with the 5 axis 10.

In the preferred form of radiant heaters these reflectors as 2, 3, are relatively small; whereas, the area to be covered by the radiant beam is usually of relatively larger dimensions, and therefore the parallel beam from the parabolic reflector of Fig. 2 does not cover a sufficient area, whereas the beam emanating from my hyperbolic reflector, (Fig. 1), may, depending upon the curvature of the hyperbola, have any degree of divergence and therefore be made to cover any required area.

In Fig. 3 is shown the effect of the rays emanating from the energy source, or heat unit 1, due to their reflection from the relatively flat surface of the back of the reflector 13, and which are returned upon the heat unit as at 14, thereby raising the temperature of that portion indicated by the black 25 area 15, to a much higher degree than the balance of the unit. This results in the early destruction of the heat unit at or about that portion indicated by the numeral 15. To overcome this I form the back of the reflector near its center with a cusp, or supplementary reflecting surface, as shown at Fig. 4, which surface may be made integral with, or mounted on, or spaced from the reflector surface 16. Such a cusp spaced from the reflector 16 is shown by the numeral 17, and it will be seen that the beam of energy emanating from the heat unit 1 will be received upon the surface of the cusp, and directed as indicated by the arrow 18, thus effectually preventing its return upon and destruction of the heat unit 1, and the distribution of the radiant energy on the reflecting surface is much better.

At 4 (Fig. 1) is shown the further path 45 of such a ray which first emanates from the heat unit 1, and is then reflected upon the surface 19, until it strikes the surface of the hyperbolic reflector 2, as at the point 20, when it is reflected again, as in the direction 50 11. A similar result is attained with the parabolic reflector 3, Fig. 2, when provided with my supplementary reflecting surface whereby the ray 7 is first reflected upon the surface of the cusp 19, impinging upon the reflector 3 at the point 21, and is reflected therefrom as indicated by the ray 22, thus effectually protecting the heat unit from destruction, and providing a radiant divergent reflected beam from those portions of 55 the heat unit, which heretofore were quickly destroyed by the returning energy from the flat surface of the reflector as at 13, Fig. 3.

The hyperbolic curve, which corresponds with the cross section through my preferred

form of reflector, is constructed as indicated 65 in Fig. 5, wherein the focii are indicated by the numerals 1 and 9. The curve 2 is then formed such that the distance from the point 24 (on the line 9—23) to the point 25 on the surface of the curve 2, plus the distance 25—1 is equal to the distance 24—26 plus the distance 26—1.

The revolution of the curve 2 about the axis 10 will produce the curve of the surface of the hyperbolic reflector; or, instead of revolving about the axis 10 the reflector may be formed of a plane surface bent into the curve 2. The focus of such a plane surface bent into said curve 2 will then be a line instead of a point, and the heat unit may 80 be suitably elongated; or, in practice the heat unit 1 may be somewhat elongated in the direction at right angles to the figures, and the surface 2 being relatively much larger than the said unit may advantageously be retained as a hyperboloid of revolution.

Moreover, in practical work the heat unit 1 is usually of a material size instead of a mathematical point, and may be of any well 90 known form, as for example, triangular in cross section in which case a greater percentage of the energy emanating from the said heat unit will be reflected from the surface of the reflector. My invention, however, is 95 directed to the shape of the reflector and the path of the rays received thereon from any heat unit mounted substantially at or about a focal center thereto, and not to a specific form of the heat unit itself.

I claim:

1. A reflector for radiant energy comprising a smooth surface of hyperbolic form, and a heat element located substantially about the focus of the curve surface in combination with a supplementary reflector of cusp form located within the first named reflector and adjacent to the heat element.

2. A reflector for radiant energy comprising a smooth surface of hyperbolic form, 110 and a heat element located substantially about the focus of the curve surface in combination with a supplementary reflector of cusp form located within the first named reflector and adjacent to the heat element, and 115 spaced therefrom to prevent heat conduction between the reflectors.

3. A reflector for radiant energy consisting of a surface of curved form and a heat element located within said curve in combination with a supplementary reflector of cusp form located within the first named reflector and adjacent to the heat element.

4. A reflector for radiant energy consisting of a surface of curved form and a heat 125 element located within said curve in combination with a supplementary reflector or cusp form located within the first named

- reflector and adjacent to the heat element and spaced therefrom to prevent heat conduction between the reflectors.
5. In an electric heater a heat element and a reflector of curved form positioned to receive radiant energy emanating from said element and to reflect the same in a divergent beam of substantially constant intensity throughout the cross section of said beam, in combination with a supplementary reflector of cusp form located within the first named reflector and adjacent to the heat element.
- 10 6. In an electric heater, a heat element located substantially at a focal point of a 15 reflector, a reflector of hyperbolic curved form symmetrically positioned with respect to and spaced from such element, and adapted to receive radiant energy from said element and reflect same as a diverging beam 20 in combination with a supplementary reflector of cusp form located within the first named reflector and adjacent to the heat element, and spaced therefrom to prevent heat conduction between the reflectors.

25 In testimony whereof, I have hereunto set my hand at San Francisco, California.

GEORGE J. HENRY.
